PLOW APPARATUS FOR HIGH SPEED SNOW REMOVAL WITHOUT WINDROWING

Jean R. Shannon, deceased, late of Clintonville, Wis., by Gladys L. Shannon, executrix, Clintonville, Wis., assignor to The Four Wheel Drive Auto Company, Clintonville, Wis., a corporation of Wisconsin

Application June 8, 1953, Serial No. 359,996

6 Claims. (Cl. 37—42)

This invention relates to methods and apparatus for high speed snow removal without windrowing. 15

This application is a continuation-in-part of the co-pending application Serial No. 35,233, filed June 25, 1948, and entitled "Methods and Apparatus for High Speed Snow Removal Without Windrowing," now Patent No. 2,651,121, issued September 8, 1953.

All conventional snowplows of the mouldboard type displace the snow laterally for a distance just adequate to clear the path of the plow, the displaced snow remaining in a windrow adjacent such path. It is a primary object of the present invention to provide a snowplow of the mouldboard type which will lift and broadcast the snow to considerable distances from the path of the plow and in a manner which does not concentrate the displaced snow in a windrow but, on the contrary, disperses it over a wide area, leaving no perceptible windrow or ridge of dangerous height. The improved method and apparatus are particularly designed for clearing airports where a windrow would be a definite hazard.

The snow is desirably lifted and thrown down wind. In order to accomplish this result, it is necessary that the plow be readily reversible as to angle so that the down wind delivery can be maintained regardless of the direction of the propelling vehicle across the path of the wind.

Reference has also been made to the high speed broadcasting of the snow. Not only must the improved plow be of such character that it will function efficiently at the maximum practical speed of the available vehicle, but there is more to the matter than merely moving the vehicle at high speed. The shape of the mouldboard must be designed in such a manner that at high speeds the snow will not come over the top and on to the vehicle windshield and, moreover, it is very important that the snow will move over the face of the mouldboard in a path to be delivered upwardly and outwardly from the end thereof and will be constantly accelerated in velocity to the point of delivery, such acceleration being due to the form of the mouldboard.

An important object of the present invention is to improve upon the mouldboard described in said prior application aforesaid by so shaping the top outer end corners of the mouldboard as to encourage the centrifugal inertia of the helically traveling snow particles to lift the particles near the end of their travel along the mouldboard and broadcast these particles down wind to a greater distance than heretofore possible. In this connection, there is provided a deflector rigidly mounted at the top edge of the mouldboard which constitutes, for the greater part of its length, a tangential extension of the mouldboard. This deflector is primarily provided to control light fluffy snow and to give it a greater trajectory than would be otherwise possible. Desirably this deflector plate also has its end portions shaped complementary with the uplifted corners of the mouldboard to cooperate with the mouldboard in lifting and broadcasting the snow for great distances laterally of the path of vehicle travel.

2

Moreover, the uplifted corner of the mouldboard and added deflector lengthens the path of travel and control of the snow particles over the mouldboard surface. This is particularly important where light snow is encountered to preclude blowing of the snow over the top of the mouldboard and onto the vehicle windshield.

In the drawings:

Fig. 1 is a diagrammatic view in front perspective showing the plow of the present invention in use and illustrating the extent to which the snow is broadcast from the plow under operating conditions.

Fig. 2 is a plan view of the mouldboard and its articulate connections to the vehicle, the vehicle being shown only fragmentarily.

Fig. 3 is a rear view of an end fragment of a mouldboard and mounting embodying the present invention, the structure of a castered blade support being shown in section.

Fig. 4 is an end view of the mouldboard and mounting of Fig. 1.

Fig. 5 is a horizontal cross section taken through the caster mounting of Fig. 2 along the line 5—5.

Fig. 6 is a fragmentary diagrammatic rear elevation of the mouldboard blade showing a slit formed in its top 25 edge prior to forming a top corner thereof.

Fig. 7 is a fragmentary diagrammatic rear view of the mouldboard blade after the top corner beyond the slit has been bent rearwardly and upwardly to expand the slit to wedge shape, a wedge-shaped insert being shown in 30 spaced relation.

Fig. 8 is a view similar to Fig. 6, but in more detail to show the structure of the blade mounting and reinforcing means, and the construction of the blade corner after the wedge-shaped insert is in place.

The mouldboard 10 is substantially of the same configuration as that described in the co-pending application aforesaid. The curve of the mouldboard in vertical section is a spiral or volute curve of progressively decreasing radius from its bottom to its top. The bottom forward edge of the mouldboard is provided with a scraping plate 11 and the top margin of the mouldboard desirably terminates in an upwardly and rearwardly directed flange 12 substantially at a right angle to the blade margin. This flange provides a mount for a deflector plate 13, 45 as hereinafter explained.

In the present construction the top corners 14 of the mouldboard are upwardly and outwardly inclined from the position which they would normally occupy in the mouldboard of my co-pending application. This construction gives the snow traveling on a helical path across the face of the mouldboard added lift at the delivery end of the mouldboard. This is because the force of the centrifugal inertia of the snow is at least partially released at the corners of the mouldboard. To fabricate these uplifted corners there is first made a short slit in the mouldboard top margin as indicated at 15 in Fig. 7. The corner portion 14 then is bodily bent or pivoted rearwardly and also its upper margin is raised, leaving the cut opened to a wedge shape. After bending, an insert 16 is welded to fill the cut as indicated in Fig. 8, to rigidify the altered structure of the mouldboard corners. The flange 12 is then secured to the top edge of the blade. The end portion 19 of the top flange 12 is separately added to the top edge of the corner 14 and is in an oblique position respecting flange 12.

Particularly where the plow is used in light, fluffy snow it is desirable to increase the effective guidance of the path of the snow under control of the mouldboard before discharge. For this purpose the top margin of the mouldboard is desirably provided with a deflector 13. This deflector comprises in the main a flat sheet 20 having a flange 21 complementary with the flange 12 of

3

the mouldboard and to which it may be rigidly attached by means of the nuts and bolts 22. The ends of the deflector plate 20 comprise substantially triangular plates 23 welded at 25 to the end margin of plate 20 and having mounting flanges 24 connected by means of bolts 26 to the flanges 19 of the mouldboard corners 14. These triangular end pieces 23 have their trailing margins upwardly and rearwardly inclined, complementary with the forward margins of corners 14 of the mouldboard. Where the plow is operating in heavier snow the deflector 13 is not necessary and may be removed by loosening the bolts 22, 26.

In the co-pending application aforesaid, there are disclosed elongated ski runners having a castered connection to support the blade near its ends. These ski runners were supported on spaced vertical bearing brackets 28, 29, 36 and 37. Under some conditions castor wheels are desired. For that purpose there may be provided the castor wheel structure shown in Figs. 3-5 in this application and in which the castor wheels 30 and their mountings are interchangeable with the runners shown in said co-pending application and in Fig. 2 herein. Each castor wheel 30 is provided with the usual yoke 31 spanned by the wheel axle 32. Offset on its vertical axis from axle 32 is the swiveling tube 33 telescopically receivable in a complementary bearing tube 34 welded or otherwise fixed to the spaced bracket plates 35 which embrace the square blocks 46 and 47 which are normally mounted between the brackets 28, 29 and 36, 37 on the retaining pins 48 and 49 respectively. The plates 35 are fastened to the blocks 46 and 47 by bolts 59 which pass laterally through the blocks 46, 47, and aligned transverse bores in the pins 48, 49. Engagement of the inner faces of plates 35 with the side edges of brackets 28, 29, 36 and 37, precludes pivoting of the blocks 46 and 47. Accordingly the castor mounting is rigid respecting the mouldboard, except for swiveling of the tube 33 in bearing tube 34. Each castor and its mount is removable by removing bolts 50.

ing bolts 50. Mounted within the swiveling tube 33, on the cross disk 38, is a compression spring 39 having a collar 40 fast to a pilot rod 41 about which the spring is coiled. The position of the collar 40 is adjustable by moving the backing nut 42 on threads 43. These threads also engage complementary threads in cap 51 mounted on bearing tube 34. Rod 41 extends through an aperture in the cross disk 38 so that the weight of the mouldboard is imposed on the cross disk 38 through the spring 39. The spring cushions road shock. The overall height of the mouldboard respecting the caster can be adjusted by turning the pilot rod 41 by means of its squared head 44 and adjusting the lock nut 45. This, of course, advances or retracts the pilot rod threads 43 respecting complementary threads in the cap 51 on tube 34.

The caster wheels 36 accommodate for pivotal movement of the mouldboard about the vertical axis pivots 52 on which the mouldboard is mounted on the vehicle for oscillation in a horizontal plane. Thus the caster is always aligned in a direction of vehicle travel regardless of the angular position of the mouldboard respecting the path of vehicle travel. This is important in a high speed snowplow in order that the inclination of the blade be changed at the end of each pass of the plow. Regardless of the inclination, the wheels always align in the direction of vehicle travel.

As explained in the co-pending application, aforesaid, and as best shown in Figs. 2 and 4 of the instant application, the mouldboard blade is mounted for articulation in both horizontal and vertical planes. The rear convex face of the mouldboard 10 is provided with a reinforcing and mounting bracket 55 which includes bracing angle members 56 and a cross connecting member 64. The bracket 55 has a substantially planiform rear face 57 in thrust engagement with a thrust member 58 which has a substantially planiform front face 59 complementary to the rear face 57 of the mounting bracket

55. The bracket 55 is pivotally connected to the thrust member near its bottom on a horizontal pivot 60 on which the mouldboard may oscillate in a vertical plane. As more fully described in the co-pending application aforesaid, the bracket 55 and thrust member 58 are provided with wear pads indicated generally at 61 in Fig. 2 and which guide the bracket in its oscillatory movement on the pivot 60.

The thrust member 58 is oscillatable in a horizontal plane on the vertically spaced axially aligned pivots 52 mounted on upper and lower yokes 62 and 63. These yokes are in turn supported on a vertically movable sub-frame comprising upper and lower links 66 and 67 pivotally connected by means of the forward and rear sets of pins 68 and 69 to the yokes and to the rigid vehicle frame members 70 respectively. The structure of the sub-frame is no part of the present invention and will not be further explained here.

As before indicated the weight of the mouldboard is carried by castered supports which may be either the caster wheels 30 shown in Figs. 3 and 4 or the caster shoes or runners 71 shown in Fig. 2. These caster supports align in the direction of vehicle travel and will raise and lower the mouldboard to accommodate for ground irregularities. The parallelogram links 66 permit bodily movement of the mouldboard respecting the vehicle in a vertical plane and the pivot 60 permits oscillation of the mouldboard in a vertical plane. The angular position of the mouldboard respecting the path of travel of the vehicle is set by the hydraulic motor indicated generally as 72. The motor has a piston 75 and a pivotal connection at 76 to a bracket 77 on the thrust member 58. As indicated in the application aforesaid, means are also provided for lifting the entire mouldboard and its castered supports from the ground for transportation from point to point. This means includes the hydraulic motor 78 which acts upwardly on the chain links 79 and 80. These elements are no part of the present invention, however, and will not be further described.

The mouldboard is ordinarily kept in either of its extreme positions of angular adjustment during use. In practice, it has been found desirable for the particular mouldboard shown to be set at an angle of approximately 50° from the longitudinal center line of the vehicle. At this approximate angle, the height of the mouldboard from its cutting blade 11 to the upper edge thereof, and the curvature of the mouldboard as shown, cause a particle of snow picked up at any point along the cutting blade 11 to travel in a helical path up and across the curved face of the mouldboard to, or near to, the discharge end. In traversing this path, the particle of snow so picked up will follow a curve of uniformly decreasing radius and will therefore be uniformly accelerated all the way to the discharge point. When the snow particles reach the uplifted corners 14 the force of their centrifugal inertia is at least partially released and the snow particles project themselves along the outwardly and upwardly inclined corners of the blade to a greater height than would otherwise be possible to receive the down wind draft aforesaid. From this greater height the snow is carried farther by the wind than heretofore. The high velocity discharges widely distributes all particles of snow and, as above noted, the plow is ordinarily used cross wind and arranged to discharge down wind so that the wind assists in distributing the particles of snow as widely as possible, virtually none of them falling in the immediate vicinity of the path of the plow.

As distinguished from normal plowing operations which simply displace the snow sufficiently to clear a traveled roadway, and which ordinarily proceed at a speed such that the snow is merely displaced sufficiently for clearance, the present invention is conducted at as high a speed as is possible with the apparatus used, and with due consideration for the weight of the snow to be displaced. Desirably the plow should develop sufficient

speed so that the snow, instead of merely being pushed laterally, is actually lifted from the road and projected upwardly and outwardly from the end of the mouldboard at such high velocity that the passage of the plow leaves no perceptible windrow whatever.

Since the ordinary runway to be cleared is many times wider than the plow, it is usually necessary to make a number of traverses of the runway before the runway is clear. Each such traverse is made at comparatively high rates of speed, which, in actual practice, has approximated at least 27 miles per hour or more. This compares with a speed of approximately ten miles per hour at which snow plowing operations were generally being conducted prior to the filing of the parent application above identified. The difference in speed results in a totally different kind of operation, since the purpose of ordinary plowing is merely to push the snow aside, whereas as the result of plowing according to the present method is to lift the snow bodily and project it to a distance, leaving it distributed. In each such traverse, the successive particles of snow encountered by the blade are impacted with sufficient velocity to lift them and cause them to travel a helical path upwardly and outwardly along the blade to be projected upwardly and outwardly from the end of the blade. The velocity of projection is such that substantially all of the snow encountered in each traverse will be hurled not only free of the runway, but distributed over a wide area therebeyond, thus avoiding formation of a windrow.

In ordinary plowing operations with conventional plows, the plowing operation is ordinarily started at the center of the road or runway, and the snow is pushed first to one side and then to the other until the entire area has been cleared, leaving the snow in windrows at opposite sides of the cleared path. According to the present method of operation the plowing is preferably commenced at the upwind side of the runway or road to be cleared, and the plow is operated at a minimum speed of approximately 27 miles per hour, taking a cut of snow which is not too heavy to permit operation at the appropriate speed to raise and project such snow downwind beyond the runway and effect its distribution over a wide area. Arriving at the end of the path to be cleared, the vehicle is turned around, and the angle of the plow is reversed, thereby continuing to throw the snow down wind. As many traverses are made as may be required to complete the clearing of the runway to the desired width, throwing all of the snow to the downwind side of the runway and so distributing it as to leave no substantial windrow. The snow is lifted bodily and thrown so far that little of it needs to be rehandled. Even in the first traverse along the upwind side of the runway, much of the snow will be thrown clear of the runway on the down wind side. In successive traverses, therefore, the snow will be distributed at progressively greater distances from the runway.

There is claimed:

1. A snowplow comprising the combination with a propelling vehicle adapted for high speed travel, of a mouldboard blade set obliquely with respect to the path of vehicle travel and having a forwardly directed concave surface progressively decreasing in radius from the bottom to the top thereof, the height of said blade being sufficient so that material encountered thereby will be lifted and progressively increased in angular velocity in traversing a helical path along said blade, an end corner at the top of the blade being upwardly and outwardly inclined from said concave surface and comprising a substantially tangential extension of said concave surface to permit the material to lift before it leaves the blade for

dispersion in the course of its centrifugal discharge from the blade.

2. The device of claim 1 in further combination with a detachable deflector, the top edge of the blade being provided with a mounting strip to which the deflector is detachably mounted, said mounting strip comprising a first section along the top edge of the blade proper and an inclined section along the top edge of the inclined corner of the blade, said deflector comprising a flat plate portion connected to the said first strip section, and having an inclined end portion complementary to the inclined corner portion of the blade and connected to the said inclined strip section.

3. A snow plow mouldboard comprising a forwardly directed concave surface over which the material encountered in the advancing movement of the blade will be confined to traverse a helical path along said blade under pressure of the advancing blade until discharged from the end thereof, the end corner at the top of the discharge end of the blade being upwardly and outwardly inclined respecting said curved surface and comprising a substantially tangential extension of said concave surface to permit the material to lift before it leaves the blade for dispersion in the course of its centrifugal discharge from the blade.

4. The mouldboard of claim 3 in which said concave surface progressively decreases in radius from the bottom to the top thereof whereby said material increases in velocity in traversing said helical path prior to encountering said corners.

5. The mouldboard of claim 3 in which the junction of said end corner with the blade comprises a wedge-shaped insert welded to said blade and corner to increase the lineal dimension of the mouldboard along its top edge and rigidify the end corner in its inclined position.

6. A snow plow mouldboard having a curved face defining a substantially helical path for snow and a top margin with a mounting flange formed thereon, a deflector constituting an extension of the mouldboard substantially tangent to said curved face, and means for rigidly mounting said deflector to said mounting flange, the end corners of the blade top margin being upwardly and outwardly inclined from the curved blade face and comprising a substantially tangential extension of said curved face to permit the snow to lift before it leaves the blade for dispersion in the course of its centrifugal discharge from the blade, said deflector comprising a flat plate between the inclined portions of the blade and having inclined ends complementary to the inclined corner portions of the blade.
